(57) CLAIM

The ornamental design for a front bumper for an automobile as shown and described.

DESCRIPTION

FIG. 1 is a first perspective view of a front bumper for an automobile showing our new design;

FIG. 2 is a second perspective view thereof;

FIG. 3 is a front elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines shown in the drawings depict portions of the front bumper for an automobile that form no part of the claimed design. The grayscale shading of the drawings depict the shape of the three-dimensional surface and do not represent any particular colors.
